Application January 19, 1949, Serial No. 71,602

12 Claims. (Cl. 209—81)

1

This invention relates to a can sorting machine and more specifically to a machine adapted to the identification and sorting out of improperly labeled cans.

It has been found, where cans of the same size having different labels lithographed thereon are used to package the different materials or substances identified by such labels, that on occasion cans designated as containing a certain substance are improperly filled with another. This results from cans having different labels becoming mixed together and not being readily discerned by the operator of the machine used to fill and seal the cans because of the identity of size and shape of the cans and often because of the similarity of the lithographed markings on the cans themselves. The present invention is directed to the provision of an apparatus which is entirely independent of the personal element and which will positively identify and reject such cans whose labels differ from those of the cans intended to be filled with a particular substance.

This is accomplished by the use of code marks which are formed on the can surface at the same time that the surface is being lithographed with its designation. These marks comprise a pair of small exposed areas of metal whose position upon the cylindrical can surface corresponds to a particular can label. The apparatus embodying the present invention is adapted to identify by electrical means cans having the desired code markings and reject all those not so marked. The apparatus is positive in its operation. Only cans having the proper code markings will produce the signal which will operate the means which accepts the cans, thus providing for failure of the equipment which will automatically result in all cans being rejected. The apparatus is so designed that an impulse caused by poorly lithographed cans or improper passage of the cans through the machine will not function to operate the machine to accept such cans. Only an impulse of definite amplitude and duration will operate the mechanism.

It is, therefore, an object of the present invention to provide an improved apparatus which is adapted to identify and sort out improperly labeled cans.

It is a further object of this invention to provide an apparatus of this kind which is positive in its operation in accepting properly coded cans, rejecting all others.

It is a still further object of this invention to provide an apparatus of the class described which is adapted to be used with cans having

2

code marks thereon comprising small exposed metal areas.

It is a still further object of this invention to provide an improved apparatus which is adapted to identify and accept, through the functioning of an electric signal, properly labeled cans.

It is a still further object of this invention to provide an apparatus of the class described which may be readily modified for the identification of cans having different code marks.

It is a still further object of this invention to provide a can sorting apparatus of the class described which is relatively simple in its construction and foolproof in its operation.

Other objects and advantages of the invention will become apparent from the following description taken in connection with the accompanying drawings, and it will be understood that many changes may be made in the details of construction and arrangement of parts shown and described without departing from the spirit of the invention as expressed in the accompanying claims. We, therefore, do not wish to be limited to the exact details shown and described as the preferred form only has been shown by way of illustration.

In the drawings:

Fig. 1 is a plan view of a can identification and sorting apparatus embodying the present invention;

Fig. 2 is a side elevational view of the apparatus of Fig. 1;

Fig. 3 is a sectional view of the apparatus taken on the line 3—3 of Fig. 2;

Fig. 4 is a perspective view of a can such as is intended to be sorted by the herein described apparatus; and

Fig. 5 is a wiring diagram illustrating the electrical circuit and connections by which the signal is generated for the identification and accepting of a properly coded can.

In the apparatus illustrated in Figs. 1 to 3, cans 10 are fed, one by one, into the apparatus between the belts 11 and the contact bars 12. The belts 11 serve a dual purpose. They hold the cylindrical surface of each can in intimate contact with the bars 12 and, secondly, propel the can through the apparatus by rolling it along the said bars. Each belt 11, of which there are preferably two, is driven between a pair of pulleys 13 and 14. The pulleys 14 are freely rotatable upon a vertical shaft 15, while the pulleys 13 are fixed to the vertical shaft 16 which is rotated through the medium of the pulley 17 and the drive belt 18. The belt 18 is itself driven by

means of a pulley 19 connected through conventional gear reduction means 20 with the motor 21. The belts 11 are themselves sufficiently resilient and so spaced from the contact bars 12 that a can thrust therebetween is readily grasped and rolled along in contact with the bars, until it emerges at the other end into the chute 22.

The contact bars 12 constitute elongated electrical contacts which extend somewhat less than the length of the belts 11. While seven such bars are illustrated, the contact of only two bars with the two code marks 31 on a can serves to identify a particular can. By using seven bars, however, twenty-one different combinations of pairs of bars are possible and the apparatus may thus be employed to identify twenty-one different codes merely by varying the electrical connections to the bars, as will be clearly understood from the description of the electrical circuit and its operation which is given below. The bars 12 are preferably made of stainless steel rather than copper because of the former's greater resistance to wear and the much smaller likelihood of its corroding. These bars are mounted at each end in slots formed in the upright supports 23, which themselves are made of a nonconducting material to insulate the bars from each other. To provide a more positive contact between each of the bars 12 and the can 10, the bars may be loosely mounted in the slots in the supports 23, there being small rubber inserts in the bottom of the slots to resiliently press each bar into intimate contact with the can. The use of such a feature will permit the bars to be made and mounted within less exacting tolerances and will also provide the requisite contact between bars and can despite small deformations in the latter. The supports 23, like the pulley shafts, gear reduction means, motor, etc. are mounted securely upon the supporting frame 24.

Each can after emerging from between the belts and the contact bars travels along the chute 22 and, if not identified as a properly coded can, will continue therealong to a discard receptacle (not shown). However, if properly coded, a can will in passing between the belts and bars cause the electrical circuit to generate a signal, as will be described below, which signal will cause the solenoid 25 to swing a gate 26 by means of the lever mechanism 27 into the path of the chute, thereby deflecting the can therefrom into a second path or chute 28. The latter leads to a bin or receptacle (not shown) which receives the properly coded and, therefore, correctly labeled cans.

The electrical circuit, which is employed to provide the signal when a properly coded and labeled can is passed through the above-described apparatus, includes two direct current voltage sources 29 and 30 which are connected in opposition and, being of equal potential, ordinarily have no effect in the circuit. The two bars which are to serve to identify a particular can are connected across the source of voltage 30. For purposes of illustration, the two lowermost of the seven bars 12 in Fig. 5 are so connected and will, upon contacting the code marks 31, produce the signal which will actuate the solenoid 25 to cause it to swing the gate 26 across the path of chute 22 to bypass the can into chute 28. The remaining five bars are connected together and with one of the two bars connected across voltage source 30 are connected across voltage source 29 as shown in Fig. 5. The above-described signal will only be generated when the grid-controlled rectifier 33

is conducting but this is prevented by the small negative voltage impressed upon the rectifier grid by the battery 32. However, when a can having code marks 31, which are adapted to contact the lowermost pair of bars 12, passes through the apparatus, the can will short out voltage source 30 upon contact being made between the code marks and the bars. This upsets the balance of the two voltage sources 29 and 30 and, since each of the latter is of higher potential than battery 32, a resultant positive voltage is impressed upon the grid of the rectifier tube 33 with the result that the tube begins to conduct the current generated by battery or voltage source 34, the latter producing a considerably higher potential than battery 32. This closes the relay 35 which, in turn, closes the solenoid circuit (not shown) and the solenoid 25, thus actuated, swings gate 26 into chute 22 to divert the can into the path 28.

In order that the relay 35 will be held closed for a period long enough to enable the can to continue along the bars and finally pass through the gate 26, an adjustable time delay is built into the rectifier circuit. The adjustable time delay means comprises the condenser 36, the variable resistance 37 and the gaseous discharge tube 38. The code marks 31 having made and then broken contact with the pair of bars 12, the gas-filled, rectifier tube 33 continues to conduct the current in the relay circuit. How long the relay will remain closed will depend upon the electrical values of the condenser 36, the resistance 37 and the gaseous discharge tube 38. When conduction of the rectifier 33 first begins, the current of the relay circuit starts charging condenser 36 through the variable resistance 37. When the critical breakdown voltage of the gaseous discharge tube 38 is reached, the condenser 36 discharges therethrough, thus momentarily dropping the plate voltage of rectifier 33 to zero which extinguishes the rectifier to open up the relay. The time elapsed between the first contact of the code marks 31 and the bars 12 and the dropping out or opening of the relay 35 will be at least as great, and preferably somewhat greater, than the time required for the can to continue along the bars after making the said contact, pass along the chute 22 and through the gate 26. The time that elapses between the closing and opening of the relay can, of course, be varied by manipulation of the adjustable resistance 37.

To prevent accidental firing or the conduction of the tube 33 several precautions are taken. It is possible that poorly lithographed or coded, or deformed cans, or the improper passage of the cans through the apparatus may cause a momentary "signal" voltage to be impressed upon the grid of the tube 33. To avoid firing of the tube under such circumstances, a parallel condenser 39 is incorporated in the circuit to resist any sudden, momentary change from negative to positive of the voltage impressed upon the grid of tube 33. The capacity value of 39 will determine of what duration and amplitude an impulse must be to operate the apparatus. A second precaution taken is the use of two grounding bars 40, one of which is mounted in each of the upright supports 23. These bars are so positioned that each overlaps the ends of the contact bars 12, as noted in Figs. 1 and 2. These, too, serve to prevent transient voltages and possible resulting signals, which might otherwise occur under such as the following conditions. When a can first comes into contact with the vertical strip of

exposed metal 44, which includes the seam or solder joint 41 as seen in Fig. 4, will be the portion of the peripheral surface of the can, rather than the lithographed area 42, to first contact the ends of the bars. Due to the difficulty of properly aligning the ends of the bars, especially if these are spring pressed or mounted on rubber inserts as discussed above, it is very possible that the exposed metal strip may make instantaneous contact with only a few of the bars. Depending upon the particular connection of these few bars within the electrical circuit, this can well result in transient voltages in the circuit, causing the grid-controlled rectifier 33 to begin conducting. One grounding bar 40 is so positioned, however, that the cans are caused to contact it just prior to engaging the plurality of contact bars. Thus, any voltage differential across a can, caused by the vertical strip or seam of the can not making instantaneous contact with all the contact bars, is grounded out by the bar 40 through the circuit as shown in Fig. 5. In like manner, a second grounding bar 40 is positioned in overlapping relation with the other ends of the plurality of bars 12 to preclude a similar effect occasioned by the vertical seam of the can passing over the ends of the bars as the can leaves the bars. Here the grounding bar 40 extends beyond the ends of the contact bars 12 to ground out improper voltage differentials across the can, as in the first instance.

No specific electrical values are given for the various elements shown in Fig. 5 for these are interrelated and may be readily determined by one skilled in the art. Some will depend upon the physical dimensions of the apparatus; thus, the values of the elements of the time delay means will depend upon the distance between the contact bars and the gate. A number of variable resistances have been incorporated in the circuit, too, for purposes of adjustment as will be obvious to those skilled in the art. While we have depicted in the wiring diagram the several voltage sources as batteries, obviously, any source of direct current potential is satisfactory; such voltages may, in fact, be provided from a single source of alternating current by the use of suitable transformers and rectifiers.

The apparatus, described herein, is intended for use with cans having any type of coating or covering thereon, comprising the label, which is non-conducting and through which the metallic surface of the can may be exposed to provide a pair of code markings. Preferably such cans will be of the lithographed variety, the label being printed or impressed directly upon the can and completely encircling the periphery except for the narrow strip in which the joint occurs. When the plurality of bars 12 pass over this strip of exposed metal, the voltage of both batteries 29 and 30 are shorted through the can, the resultant voltage of 29 and 30 is still zero, and no signal is produced to operate the gate 26. Only when the single battery 30 is shorted, through contact of the code marks with the pair of bars connected across battery 30, is an adequate signal given which will operate the gate. The cans should be fed past the bars one at a time in order that conflicting signals may not be given. We have found that the cans are best assorted after they are filled and sealed, since these offer greater resistance to deformation caused by the pressure exerted on them by the bars 12 and belts 11. Moreover, the cans, emerging at regular intervals from the sealing machine, automatically provides the proper

spacing to preclude more than a single can passing along the bars at one time. However, the apparatus is well adapted to the identification and sorting of cans prior to their being filled to insure that only cans properly labeled are fed into the filling machine.

While the wiring shown in Fig. 5 is intended for the identification of cans having code marks adapted to make contact with the lowermost pair of bars 12, any two of the plurality of bars may be connected across the battery 30 to identify cans having code marks which will coincide with these two bars, the remaining five bars being connected as a unit to the positive terminal of battery 29. The apparatus, herein described, may also be readily adapted for use with cans of different sizes. This is accomplished by making the contact bar assembly and the belt and drive mechanism relatively movable, in order that the distance between the belts 11 and the bars 12 may be varied to accommodate cans of different diameters. While we have described the operation of the gate being effected by a solenoid, other electrically actuated means, known to those skilled in the art, for converting the signal to a physical sorting of the cans may be employed in accordance with this invention.

From the foregoing description, it will be apparent that we have provided means for obtaining all of the objects and advantages of this invention.

What we claim and desire to secure by Letters Patent of the United States is:

1. A sorting machine for cans having a pair of exposed metal areas or code marks on the surface thereof comprising a plurality of contacts, means for moving said cans across the plurality of contacts, a gate movable into the path of the cans beyond said plurality of contacts to divert the cans from said path, electrically actuated means for moving the gate into the path, an electrical circuit connecting the electrically actuated means to the plurality of contacts, two sources of voltage in said circuit, the voltages being in opposition and balanced to ordinarily have no effect upon the electrically actuated means, two of said contacts being connected across one of the voltage sources, the remainder of the contacts and one of said two contacts being connected across the other voltage source, whereby, when said two contacts simultaneously make contact with the code areas of a can, the one source of voltage is shorted through the can, thereby unbalancing the opposed voltages to operate the electrically actuated means whereby the gate is moved to divert the can from said path.

2. A sorting machine for cans having a pair of exposed metal areas or code marks on the surface thereof comprising a plurality of contacts, means for rolling said cans across the plurality of contacts, a gate movable into the path of the cans at a point beyond said plurality of contacts to divert the cans from said path, electromagnetic means adapted to move the gate into the path, an electrical circuit connecting the electromagnetic means to the plurality of contacts, two sources of voltage in said circuit, the voltages being in opposition and balanced to ordinarily cause no signal whereby the electromagnetic means is not effected thereby, two of said contacts being connected across one of the voltage sources, the remainder of the contacts and one of said two contacts being connected across the other voltage source, whereby, when said two

contacts simultaneously make contact with the code areas of a can, the one source of voltage is shorted through the can, thereby unbalancing the opposed voltages to cause a signal which operates the electromagnetic means whereby the gate is moved to divert the can from said path, and means in said electrical circuit adapted to allow only a variation of a predetermined minimum amplitude and duration in the net potential of the opposed voltages to cause a signal.

3. A sorting machine for cans having a pair of exposed metal areas or code marks on the surface thereof comprising a plurality of elongated contacts, means for rolling said cans longitudinally along the plurality of contacts, a gate movable into the path of the cans at a point beyond said plurality of contacts to divert the cans from said path into a second path, electromagnetic means adapted to move the gate into the path, an electrical circuit connecting the electromagnetic means to the plurality of contacts, two sources of voltage in said circuit, the voltages being in opposition and balanced to ordinarily provide no signal to actuate the electromagnetic means, two of said contacts being connected across one of the voltage sources, the remainder of the contacts and one of said two contacts being connected across the other voltage source, whereby, when said two contacts simultaneously engage the code areas of a can, the one source of voltage is shorted through the can, thereby unbalancing the opposed voltages to provide a signal capable of actuating the electromagnetic means whereby the gate is moved to divert the can into said second path, and time delay means in said electrical circuit to continue said actuation of the electromagnetic means after contact between the elongated contacts and code areas is broken for a period of sufficient duration to enable the can which has caused the signal to pass said gate into said second path.

4. A sorting machine for cans having a pair of exposed metal areas or code marks on the surface thereof comprising a plurality of parallel contact bars, a driven belt adapted to roll said cans lengthwise along the contact bars, means for conducting the cans along a predetermined path beyond the ends of said contact bars, a gate movable into the path of the cans at a point beyond the contact bars to divert the cans from said path, electromagnetic means adapted to move the gate into the path, an electrical circuit connecting the electromagnetic means to the contact bars, two sources of voltage in said circuit, the voltages being in opposition and balanced to ordinarily cause no signal to actuate the electromagnetic means, two of said contacts being connected across one of the voltage sources, the remainder of the contacts and one of said two contacts being connected across the other voltage source, whereby, when said two contacts simultaneously engage the code areas of a can, the one source of voltage is shorted through the can, thereby unbalancing the opposed voltages to cause a signal which actuates the electromagnetic means which moves the said gate into the path of the can, means in said electrical circuit adapted to allow only a variation of a predetermined minimum amplitude and duration in the net potential of the opposed voltages to cause a signal, and time delay means in said circuit to continue said actuation of the electromagnetic means after contact between the contact bars and code areas is broken for a period of sufficient duration to enable the can which has caused the signal to be diverted by said gate.

5. A sorting machine for cans having a pair of exposed metal areas or code marks on the surface thereof comprising a plurality of parallel contact bars, a pair of driven belts spaced from said bars and adapted to roll said cans lengthwise along and in contact with said bars, a chute for conducting the cans along a predetermined path beyond the ends of the contact bars, a gate movable across the chute to divert cans therefrom into a second path, a solenoid adapted to operate the gate, an electrical circuit interconnecting the solenoid and the contact bars, two sources of voltage in said circuit, the voltages being in opposition and balanced to ordinarily produce no signal capable of actuating the solenoid, two of said contact bars being connected across one of the voltage sources, the remainder of the contact bars and one of said two contact bars being connected across the other voltage source, whereby, when said two contact bars simultaneously engage the code areas of a can, the one source of voltage is shorted through the can, thereby unbalancing the opposed voltages to produce a signal capable of actuating the solenoid which moves the gate to divert the can from said chute into said second path.

6. A sorting machine for cans having a pair of exposed metal areas or code marks on the surface thereof comprising a plurality of contacts, means for moving said cans across the plurality of contacts, electrically actuated means beyond said plurality of contacts adapted to selectively direct each can into one of two paths, an electrical circuit connecting the electrically actuated means to the plurality of contacts, two sources of voltage in said circuit, the voltages being in opposition and balanced to ordinarily provide no signal which is capable of effecting said electrically actuated means, two of said contacts being connected across one of the voltage sources, the remainder of the contacts and one of said two contacts being connected across the other voltage source, whereby, when said two contacts simultaneously make contact with the code areas of a can, the one source of voltage is shorted through the can, thereby unbalancing the opposed voltages to provide a signal which effects the electrically actuated means to direct the can into one of said two paths.

7. A sorting machine for cans having a pair of exposed metal areas or code marks on the surface thereof comprising a plurality of contact bars, means for rolling said cans longitudinally along the plurality of bars, a gate movable into the path of the cans at a point beyond said plurality of contact bars to divert the cans from said path into a second path, electrically actuated means adapted to move the gate into the path, an electrical circuit capable of providing a signal which will effect said electrically actuated means, said circuit including a pair of sources of voltage connected in opposition and so balanced as to preclude said circuit from ordinarily providing said signal, a connection from the negative terminal of both voltage sources to one of said contact bars, a connection from the positive terminal of one of said voltage sources to a second contact bar, and a connection from the positive terminal of the second voltage source to the remainder of the contact bars, whereby, when said first two bars engage the code areas of a can, one source of voltage will be shorted through the can, thereby unbalancing the opposed voltages in said circuit to provide the signal effecting the electrically

actuated means whereby the gate is moved to divert the can into said second path.

8. A sorting machine for cans according to claim 7 in which a time delay means is included in said circuit, comprising a condenser and gaseous discharge tube, to continue said signal, after contact between the bars and code areas is broken, for a period of sufficient duration to enable the can which has caused the signal to pass said gate into said second path.

9. A sorting machine for cans having a pair of exposing metal areas or code marks on the surface thereof comprising a plurality of contact bars, means for rolling said cans longitudinally along the plurality of bars, a gate movable into the path of the cans at a point beyond said plurality of contact bars to divert the cans from said path into a second path, electromagnetic means adapted to move the gate into the path, an electronic circuit including a grid-controlled rectifier which is adapted to produce a signal which will actuate the electromagnetic means when a voltage of correct polarity is impressed upon the grid of the rectifier, a pair of sources of voltage in the grid circuit which are in opposition and so balanced as to preclude the electronic circuit producing said signal, a connection from the negative terminal of both voltage sources to one of said contact bars, a connection from the positive terminal of one of said voltage sources to a second contact bar, and a connection from the positive terminal of the second voltage source to the remainder of the contact bars, whereby, when said first two bars engage the code areas of a can, one source of voltage will be shorted through the can, thereby unbalancing the opposed voltages to impress a voltage of correct polarity upon the rectifier grid whereby a signal will be given to actuate the electromagnetic means to move the gate and divert the can into said second path.

10. A sorting machine for cans according to claim 9 in which a time delay means is included in said electronic circuit, adapted to continue the signal to continue actuation of the electromagnetic means, after the contact between the bars and the code areas is broken, for a period of sufficient duration to enable the can which has caused the signal to pass and be diverted by the gate.

11. A sorting machine for cans according to claim 10 in which means is included in the grid circuit, adapted to allow only a variation of a

predetermined minimum amplitude and duration in the net potential of the opposed voltages to cause the electronic circuit to produce said signal.

- 5 12. A sorting machine for cans having a pair of exposed metal areas or code marks on the surface thereof comprising a plurality of parallel contact bars, a driven belt adapted to roll said cans longitudinally along the plurality of bars, a chute for conducting the cans along a predetermined path beyond the ends of the contact bars, a gate movable across the chute to divert cans therefrom into a second path, electromagnetic means adapted to operate the gate, an electronic circuit adapted for the production of a signal which will actuate said electromagnetic means, two sources of voltage in said circuit which are in opposition and so balanced as to preclude the circuit producing said signal, a connection from the negative terminal of both voltage sources to one of said contact bars, a connection from the positive terminal of one of said voltage sources to a second contact bar, and a connection from the positive terminal of the second voltage source to the remainder of the contact bars, whereby, when said first two bars contact the code areas of a can, one source of voltage will be shorted through the can, thereby unbalancing the opposed voltages to cause a signal in said circuit which actuates the electromagnetic means which moves the gate to divert the can from said chute into said second path.
